CLAIM

The ornamental design for a wafer carrying-in/out apparatus or the like, as shown and described.

DESCRIPTION

FIG. 1 is a front elevational view of a wafer carrying-in/out apparatus showing our design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a top, front and right side perspective view thereof; and,

FIG. 8 is a top, front and right side perspective view thereof shown with the doors thereof in an open position.
